(57) **CLAIM**

The ornamental design for a pair of earphones with charging case, as shown and described.

DESCRIPTION

FIG. 1 is a perspective view of a charging case of a pair of earphones with charging case shown separately to show aspects of the design that are not visible when combined, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a pair of earphones of the pair of earphones with charging case shown separately to show aspects of the design that are not visible when combined;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the pair of earphones with charging case shown combined.

The dash-dash broken lines in the drawings depict portions of the pair of earphones with charging case that form no part of the claimed design.
